UNITED STATES PATENT OFFICE.

VALENTINE G. SCHUCK, OF NEW YORK, N. Y., ASSIGNOR TO THE SUTRO BROS.
BRAID COMPANY, OF SAME PLACE.

DESIGN FOR BRAID.

SPECIFICATION forming part of Design No. 23,208, dated April 24, 1894.

Application filed November 13, 1893. Serial No. 490,843. Term of patent 14 years.

To all whom it may concern:

Be it known that I, VALENTINE G. SCHUCK, of the city, county, and State of New York, have invented and produced a new and original Design for Braid, to be used by way of ornamentation and in trimming garments &c., of which the following is a full, clear, and exact description, reference being had to the accompanying drawings, wherein—

10. Figure 1 is a front view of the design, and Fig. 2 is a sectional diagram on line $x-x$ of Fig. 1, which show the arrangement of the strands, the colors of which may be varied so as to produce different effects but without changing the design.

The design consists of a Soutach braid having two interlocked central cords or strands $b b$ of uniform size running in an undulating parallel, on each side of which, and forming 20 the edge of the braid, is a much smaller cord or strand which conforms to the undulations of the cord or strand to which it is interlocked. The smaller cords or strands are shown at a and, with respect of each other, are of uniform size. The front face of the braid in said 25 design presents the appearance of a well defined central undulating groove c along the

interlocking line between the cords or strands $b b$, and a slight indentation along the interlocking of the marginal cord or strand a to 30 its adjacent central cord or strand. The two marginal cords or strands conforming to the undulations of the central cords or strands give to the braid the appearance of being alternately scalloped on its respective edges. 35

I am aware of the existence of braid which presents a serpentine or zigzag effect but it will be observed that the design for which I claim a patent differs from all others in the well defined central undulating groove, the 40 two undulating parallel cords or strands of uniform size and the adjacent smaller marginal cords or strands presenting when complete the distinguishing characteristics here- in described. 45

Having thus described my invention, I claim—

The design for a braid herein described, and illustrated in the accompanying drawings.

VALENTINE G. SCHUCK.
